EMBLEM DISPLAY BAR FOR SNOWMOBILE

Glen Edward Marose, Des Moines, Iowa, assignor to Snowmobile, Ltd., Des Moines, Iowa

Filed Nov. 10, 1970, Ser. No. 25,915

Term of patent 14 years

Int. Cl. D12—16; D11—05

U.S. Cl. D14—6

FIG. 1 is a perspective view of the emblem display bar for a snowmobile;

FIG. 2 is a top view thereof;

FIG. 3 is a side elevational view thereof;

FIG. 4 is an elevational view thereof as seen from the right of FIG. 3;

FIG. 5 is an elevational view thereof as seen from the left of FIG. 3;

FIG. 6 is a perspective view of a modification of the design; and

FIG. 7 is a detailed elevational view of the upper end of the device shown in FIG. 6.

I claim:

The ornamental design for emblem display bar for snowmobile, substantially as shown and described.
